The Duplex Envelope Company, Inc., a corpo-
ration of Virginia

Application January 26, 1933, Serial No. 47,000

Term of patent 14 years

To all whom it may concern:

Be it known that I, CHARLES P. SCHMID, a citizen of the United States, residing in New York, in the county of New York and State of New York, have invented a new, original, and ornamental Design for a Container for Church Offering Envelopes, of which the following is a specification, reference being had to the accompanying drawing forming part hereof.

In the drawing:

Fig. 1 is a perspective view of the container showing my design, the container being shown in erect position with the front, top and one end in view, and

Fig. 2 is a perspective view of the container turned from the position shown in Fig. 1 to show the back, bottom and remaining end.

The container represents a treasure chest and on the front there is a representation of a sheet of parchment or the like nailed to the chest and on the sheet there is wording descriptive of the religious purpose of the contents of the chest.

On the back there is a representation of a sheet of parchment or the like nailed to the chest and representation of a seal attached to the sheet. Also, on the representation of the sheet are provided spaces for the name and address of the user of the envelopes in the container.

I claim:

The ornamental design for a container for church offering envelopes as shown and described.
